ROTARY PUMP FOR HOT FLUIDS

George E. Bigelow, Southgate, and Arthur R. Weis, Huntington Park, Calif., assignors of one-half to Pacific Pump Works, Huntington Park, Calif., a corporation of California

Application August 1, 1938, Serial No. 222,526

15 Claims. (Cl. 103—108)

Our invention relates to rotary pumps and, more particularly, to a novel construction of a pump of this character which may be operated to pump fluids at extremely high pressures and 5 temperatures.

Although the invention has utility in various industries, it is particularly useful in the pumping of extremely hot oil under high pressure from one stage of an oil refining process to another. 10 It has been discovered that our pump gives unexpectedly improved results over the use of reciprocating pumps in this capacity, effecting a constancy of pressure which results in prolonged life of the refinery equipment, a better refining 15 action, and the production of refined products of unexpectedly better characteristics. The invention will be particularly described with reference to a rotary pump for pumping hot oil, but it will be clear that the invention is not necessarily limited thereto. 20

It is not uncommon for a pump of the type herein disclosed to receive a fluid at a temperature of 750° F. and operate at a discharge pressure as high as 2300 lbs./sq. in. The pump herein-disclosed finds particular utility in pumping hot oil 25 at a temperature from 500° F. to 850° F. and at a pressure of 500 to 2500 lbs./sq. in. Ordinary centrifugal pumps are entirely unsuited for such use and the problems encountered in the design of such a high-temperature high-pressure pump 30 are not common with those present in the design of cold-fluid or low-temperature pumps.

Pumps of the type herein-disclosed actually attain a dull cherry red color when viewed in the dark and operated at the temperatures for which 35 they are designed. Under such extreme conditions of heat, it is essential to provide a pump which maintains its alignment and sealing efficiency regardless of extreme temperature changes, and it is an object of the present invention 40 to provide such a rotary pump.

At the high temperatures to which this pump is subjected, the metal from which the pump is constructed must necessarily decrease in tensile and compressive strength. However, the problem 45 cannot be solved by the simple expedient of increasing the thickness of parts on conventional pumps. It is of paramount importance that the mass of the various elements of the pump should be so correlated with each other and with respect to various portions thereof that expansion 50 at all peripheral positions, for instance, will be substantially equal. It can be readily understood that uncompensated forces due to expansion can be extremely large. If, for example, unequal peripheral expansion of the shell or insert structure 55 of the rotary pump takes place, the resulting unequal forces will cause the heat-weakened metal to deform, with the result that accurate alignment and maintenance of sealing effective-

ness at different parts of the pump will be impossible. To that end, the invention is concerned with a structure in which expansion is so controlled as to maintain alignment of the pump parts, maintain alignment between the pump and the prime mover, and maintain all sealing means in correct sealing engagement with their mating parts, whether such sealing means be around the shaft or between the stationary elements of the pump itself. 5

Correlated expansion between the shell and the insert structure positioned therein is particularly important with relation to the problem of sealing the internal structure with respect to the shell. In the preferred embodiment of the invention we use a massive cylindrical shell with an inward-extending shoulder positioned between the inlet and outlet ports of the pump. Mating with this shoulder is an annular surface of one of the stationary pump inserts. If the shoulder 10 is formed in a plane radial to the shaft, a proper sealing action can only be maintained at this point by preventing deformation of this shoulder from its radial plane and preventing deformation of the mating annular surface from this plane. 15 To this end, it is important to use a massive cylindrical shell which is of substantially uniform thickness at all peripheral portions thereof. It is important, likewise, to apply the heat substantially uniformly to the interior of this shell. If one peripheral portion of the shell is heated more than another, or if one peripheral portion contains substantially more metal than another, the consequent difference in expansion between these peripheral portions will throw the annular shoulder out of 20 its radial plane and may result in destructive stresses. Likewise, it is desirable that the stationary pump inserts forming the insert structure should be of such character as to maintain the mating annular surface in a radial plane. 25 Uniform peripheral expansion of the shell is more important than uniform peripheral expansion of the insert structure, particularly if resilient means is provided to compensate for the excess expansion of the insert structure. Thus, various 30 types of insert structures can be used without departing from the spirit of the invention, though best results can only be obtained if all peripheral portions of the insert structure are of substantially uniform mass or thickness and are equally 35 heated by the hot fluid flowing therethrough. 40

It is an object of the present invention to correlate expansion between a shell and an insert structure therein in such manner as to maintain a seal between the inlet and outlet ports of the 45 pump. 50

Another object of the invention is to provide a sealing means between the inlet and outlet ports comprising a shoulder extending inward from a massive cylindrical shell adapted to mate 55 60

with an annular shoulder of a stationary pump insert, this pump insert extending through an opening provided by the shoulder but being free from restraint at a position therebeyond so that 5 expansive forces and fluid-pressure forces are available to maintain the annular shoulder and the mating annular portion in sealing relationship. It is another object of the invention to provide a structure in which these mating surfaces form the only seal between this insert 10 structure and the shell at said position between said inlet and outlet ports.

Another object of the invention is to provide 15 an expansion-permitting means within the shell to compensate for greater expansion of the insert structure while maintaining the parts of the pump in accurate alignment, and while maintaining a seal between the insert structure and the shell at a point intermediate the inlet and 20 outlet ports.

Another object of the invention is to facilitate 25 uniform peripheral expansion of the shell by use of detachable head members which are of substantially uniform mass at all peripheral portions thereof.

It is another important object of the present 30 invention to provide a novel pump construction including recessed heads to the end that the shaft length between outboard bearings shall be a minimum, thereby reducing vibration, decreasing 35 size, and facilitating pump maintenance.

Another object of the invention is to so support 35 the pump as to permit maintenance of equal expansion conditions of the shell and its related parts.

Another object of the invention is to provide a 40 pump which can be readily disassembled, and in which inspection of the internal surfaces near the ends thereof can be made without removal 45 of the head members or the insert structure.

Another object of the invention is to provide a 45 novel construction for preventing deposits, commonly known as "coke deposits", in such a pump and which make removal of the parts very difficult. It is a further object of the invention 50 to facilitate removal of the pump insert members by preventing extremely close contact with the shell at all peripheral portions.

Another object of the invention is to provide 55 an improved means for sealing the rotating parts of such a pump with respect to the stationary parts thereof.

Further objects and advantages will be apparent from the following description.

Referring to the drawings, which are for illustrative purposes only:

Figure 1 is a side view, partially in section, of one embodiment of the invention.

Figure 2 is a vertical cross-sectional view taken 60 on a plane represented by the line 2—2 of Figure 1.

Figure 3 is an enlarged sectional view of the sealing means between the insert structure and the shell of the invention.

Figure 4 is a sectional view, similar to Figure 2, showing an alternative construction.

Figure 5 is an enlarged sectional view of the area enclosed by the circle 5 of Figure 1.

Figure 6 is a section taken along the line 6—6 70 of Figure 5.

Figure 7 is an enlarged fragmentary section taken along the line 7—7 of Figure 2.

Figure 8 is a view, partially in section, of another embodiment of the invention.

In general, the invention includes an enclosing

structure comprising a massive cylindrical shell 11 and heads 13 and 14 detachably connected to the ends of the shell by screws means 15. Near the inlet end of the shell 11 is an inlet fitting 16 providing an inlet port 17 which preferably extends 5 radially inward to communicate with the interior of the enclosing structure. As shown, this inlet fitting 16 is threaded into an opening of the shell 11 and is then welded securely in place, as indicated at 18. Similarly mounted near the 10 discharge end of the cylindrical shell 11 is an outlet fitting 20 providing an outlet port 21.

The cylindrical shell 11 is preferably formed 15 as a one-piece forging and the wall thereof is of substantially uniform thickness throughout all peripheral sections thereof. This is particularly important as to that portion of the shell lying between the inlet and outlet ports 17 and 21, and insures substantially equal longitudinal expansion 20 at all peripheral sections which would not be the case if the shell were cast in sections and bolted together along one or more longitudinal planes. In addition to the other advantages of a forging, we have found that, by making the shell of forged material, equal peripheral 25 expansion will be obtained. Likewise, the heads 13 and 14 are preferably forged.

The inlet head 13 includes a flange 22 held 30 against the radial end surface of the shell 11 by the screw means 15. An annular rib 23 extends 35 into a corresponding counterbore of the shell 11 in which is positioned a relatively narrow gasket 24 which seals the head with respect to the shell when the screw means 15 is tightened. In general, this inlet head 13 is recessed inward to 35 provide a cavity 25 and includes, in addition to the flange 22, a boss 26 and an inward-extending wall 27, the latter providing an opening 28 which is considerably larger than the main shaft of the pump, indicated by the numeral 30. Numerous 40 advantages accrue from the use of a recessed head, including a decrease in over-all length, a shortening of the shaft with attendant decrease in vibration, and an increase in strength in that internal pressures are taken mainly by compressive 45 stresses, as distinct from tension stresses which would be present if the head structure were convexed outwardly. As shown, the cavity 25 can be made to extend inward to and beyond the end surface of the cylindrical shell 11.

Removably extending into the annular space around the shaft and inside the opening 28 is a sealing member 31 held in place by bolts 32 extending through a flange thereof and into the inward-extending wall 27 of the head. This 55 sealing member may be independently sealed with respect to the head by a gasket 33 disposed in a counterbore of the head and pressed between this head and a shoulder of the sealing member 31 entering the counterbore when the bolts 32 60 are tightened. The sealing member 31 is suitably sealed with respect to a sleeve 34 attached to the shaft, for example, by use of packing 35 compressed in a cavity of the sealing member by a suitable gland 36.

An outboard bearing 38 is provided for journaling the shaft 30 which extends therethrough to the prime mover. The use of such a bearing is very desirable as it removes the bearing surfaces from the vicinity of the hot shell and, in conjunction with other expedients to be hereinafter described, maintains shaft alignment. In addition it permits forming the heads with substantially equal amounts of material in all radial segments and at all peripheral portions and elim- 75

inates any tendency toward unequal expansion of the heads or the shell due to its generally spaced relationship. One feature of the invention is to position the bearing 38 a sufficient distance from the head so that the sealing member 31 can be moved leftward along the shaft, after removal of the gland 36, a sufficient distance to permit inspection of the interior spaces of the pump without removing the massive head 13. The preferred manner of mounting the bearing 38 is to attach it to a bracket 39 providing a ring 40 set into a cavity in the head 13 and suitably secured thereto, as by welding.

The head 14 and a bearing support for a thrust bearing 38' at the discharge end of the pump are similarly constructed and similar parts are indicated by primed numbers set forth with reference to the inlet head 13. It will be noted, however, that the boss 26' extends farther into the shell at this end of the pump so that the inward-extending wall 27' can be disposed opposite the outlet port 21, if desired. On this head, an annular ledge 42 is formed to extend into the cavity 25' to form a chamber 43 at the inner end of the cavity. This chamber will be sealed from the atmosphere by the gasket 33'. At this end of the pump, then, the sealing member 31' extends into the chamber 43 which is bounded at its inner end by the inward-extending wall 27'.

A throttle or balancing means 45 is provided at the junction of this inward-extending wall 27' and the shaft 30, best shown in Figure 5. Referring thereto, this inward-extending wall 27' includes an opening 46 into which a flanged member 47 extends and is retained therein by suitable means 48. This flanged member provides an opening 49 which is only slightly larger in diameter than the periphery of an inner rotating member 50 to provide a narrow annular passage 51 therebetween which communicates at one end with pump discharge pressure and at the other end with the chamber 43 so as to throttle any fluid flow to this chamber.

As best shown in Figure 5, this inner rotating member 50 provides a tapered part 53 which is locked on a tapered portion 54 of the shaft 30 by key means 55. The tapered portion 54 of the shaft terminates in a shoulder member or collar 56.

Also as shown in Figure 5, the sleeve 34' is threaded to the shaft 30 and provides an annular ledge 57 which engages the inner rotating member 50 to force same leftward on the tapered portion 54. To seal the threads forming the connection between the shaft 30 and the sleeve 34' against access to the hot oil, and thereby preventing "freezing" or "coking up" thereof, we provide a sealing means 58 positioned in a cavity 59 inside the annular ledge 57 and comprising packing rings which are compressed by a piston-like compression means 60 in the form of a ring of angle cross section. As the sleeve 34' is tightened, the compression means 60 engages the inner rotating member 50 to compress the packing. The material forming the ring of the compression means 60 may be a metal having a high coefficient of expansion so that it will expand when the pump becomes heated and thus compress the packing additionally.

The inner rotating member 50 and the flanged member 47 of the throttle means 45 are made of hard metal and will operate with practically no wear if materials of an abrasive or clogging character can be kept from the narrow annular passage 51. For the purpose of throwing outward

any heavy or solid materials so that they will not enter this narrow annular passage 51, we provide a plurality of rotating vanes 62 which throw such particles outward beyond the passage 51 by centrifugal force and also function to break up any large solid particles. As best shown in Figures 5 and 6, these vanes are formed by notches cut in the periphery of a ring 63 secured by screws 64 to the inner rotating member 50 at a position around the shoulder member or collar 56. These vanes are of such length as to terminate near the annular passage 51 and yet be removable along with the inner rotating member 50 through the opening 49 when inspection is desired.

This type of construction shown with reference to the heads 13 and 14 is very desirable. In addition to the advantages of the recessed heads previously mentioned, it will be noted that removal of the sealing members 31 or 31' will permit access to the internal passages of the pump without necessitating removal of the massive heads or the bearings. For example, removal of the sealing member 31 will permit inspection and cleaning of the passages at the inlet end of the pump, while removal of the sealing member 31' will permit inspection of the chamber 43 and the throttle means 45.

With regard to the internal construction of the pump, one of the important features of the invention is the provision of a removable insert 30 structure sealed with respect to the shell under varying conditions of temperature. To that end, and as best shown in Figures 1 and 3, the massive cylindrical shell 11 provides a cylindrical cavity 69 which, if desired, may be slightly counter-bored as indicated at 69'. This cylindrical cavity terminates in an annular shoulder 70 of the shell which, in turn, provides an opening 71. This annular shoulder is disposed on an annular ring 72 and is formed in a plane perpendicular to the axis of the shaft 30. An important feature of the invention is to maintain this shoulder in such a plane and to maintain the accurate mating relationship with the insert structure.

This insert structure is generally indicated 45 by the numeral 75 and includes a plurality of abutting stationary pump elements, indicated respectively by the numerals 76 to 79, as well as an outlet end member 80, which occupy the space between the shoulder 70 and the head 14. The pump element 76 is of a size to be centralized in the cylindrical cavity 69. Each pump element provides an annular recess near the periphery thereof adapted to receive a corresponding mate portion of the adjacent pump element to centralize and align these elements. If desired, pins 82 may be disposed in these recesses between the adjacent pump elements to prevent any relative rotation.

Each pump element also provides inward-extending walls 83 and 84 providing a passage 85 traversed by vanes 86. This passage receives fluid from a passage 87 of an adjacent pump element fed by a diffuser 88 held by pins 89. This diffuser 88 is disposed between these pump elements and provides vanes 90 which guide the fluid as it flows from an adjacent impeller chamber 91 into the passage 87.

The rotating structure of the pump includes a plurality of impellers 93 which are suitably keyed 70 on the shaft between the sleeves 34 and 34' and which are spaced from each other by spacers 94. These impellers may be of known design and will force fluid outward through the passages thereof and through the passage means formed by the

insert structure and including the spaces between the vanes 90, the passages 87 and the passages 85. Conventional wear rings are usually provided at the inner ends of the walls 84 around the eyes of the impellers and at the inner ends of the walls 83, but are not illustrated in Figure 1 in order to simplify the showing.

We prefer to use pump elements which are of the non-volute type and which, consequently, can be made to have walls of uniform thickness around the periphery thereof and equally spaced from the shell 11. For example, the peripheral wall outside the radial passages 87, and indicated by the numeral 95 of Figures 1 and 2, is preferably of substantially uniform thickness at all peripheral portions in a plane perpendicular to the axis of rotation of the shaft 30. By making the mass distribution of the insert structure substantially uniform about the shaft axis, we accomplish an equal longitudinal expansion of the insert structure to the end that an annular surface 96 of the pump element 76 will properly mate with the shoulder 70, irrespective of temperature changes in the pump. By this expedient, the annular surface 96 will maintain its position in a radial plane and will press against the annular shoulder 70 with substantially equal pressure at all peripheral portions, thereby overcoming defects previously experienced when the mass distribution was not substantially uniform and when one peripheral portion of the insert structure would expand longitudinally to a greater degree than another portion, thereby enormously increasing the pressure at this portion of the annular shoulder, with consequent tendency to bend or disalign the shell or the insert structure and to disalign the insert structure with respect to the rotating shaft and impellers.

Another feature of the invention is to provide an expansion-permitting packing means between the end of the insert structure 75 and a portion of the enclosing structure, preferably between the outlet end member 80 and the head 14. For this purpose, the head 14 provides an annular recess 99 containing one or more rings 100 of gasket character. Engaging this ring is the end of a cylindrical wall 101 of the outlet end member 80 whereby the expansive forces developed by the insert structure are delivered at one end to the shoulder 70 of the shell and at the other end to this insert ring 100 of gasket character. We prefer to make the insert structure of such over-all length between the annular surface 96 of the pump element 76 and the end of the cylindrical wall 101 that the ring 100 will be somewhat compressed when the head 14 is belted into place to hold the annular surface 96 against the shoulder 70. When the hot fluid is moving through the pump, the insert structure, being somewhat hotter, expands more than the cylindrical shell, with the consequence that the cylindrical wall 101 serves to compress the insert ring 100 and tighten the mating contact between the shoulder 70 and the annular surface 96. A diffuser 103 between an outward-extending wall 104 of the outlet end member 80 and the head 14 is so designed as to permit this expansive movement, for example, by forming the vanes thereof of insufficient length to bridge the space until maximum expansion has taken place. It is preferred to make the ring 100 of a material having some resiliency and the preferred construction involves the provision of some small space into which the ring can expand when compressed. An aluminum ring only par-

tially filling the corresponding recess has been found very effective in this regard.

To facilitate removal of the insert structure from the discharge end of the shell when the head 14 is removed, we prefer to use a construction best shown in Figure 2. As there shown, the lower portion 105 of the periphery of each pump element may be curved substantially the same as the cylindrical cavity 69 of the shell 11. However, the peripheral wall 95 of each of the insert structures 77 and 78 is relieved for a major portion of its periphery distance so as to form a small annular space 106 (exaggerated in the drawings for purpose of clearness) which extends about two-thirds of the way around the upper portion 15 of the pump element.

To assist in centralizing this insert structure and holding the pump inserts in such surface contact with the lower part of the shell as will preclude any tendency to form coke deposits therebetween, we prefer to use a means at the upper end of the insert structure engaging with the shell. Such a means can, likewise, serve as a substitute or supplement to the pins 82 in preventing relative rotation between the pump elements. In this connection, the preferred embodiment includes a pin or rod 107 slidable into a longitudinal groove 108 at the upper portion of the pump elements, the upper part of this rod engaging the shell 11. The pump element 79 is shown as slotted for only a portion of its length to receive the rod 107. The remaining portion, which is not relieved from peripheral contact with the shell, is indicated by the numeral 109 and terminates in contact with the wall of the cylindrical cavity 69 of the shell 11 so as to centralize this pump element and, at the same time, block the small annular space 106 to prevent such free access of the high pressure hot oil as would effect a circulation therein which would tend to fill this space 106 with a deposit of coke. Serving the same purpose is an annular wall 110 of the outlet end member 80.

In the alternative form of Figure 4, the lower portion of the pump elements is additionally relieved as indicated by the numeral 110' to provide, in effect, a plurality of pad portions engaging the shell. This expedient of further decreasing the area of actual contact between the pump elements and the shell is sometimes desirable.

To further facilitate withdrawal of the outlet end member 80, the shell 11 may be relieved at 111 throughout a major portion of the length of the cylindrical wall 101 of this outlet end member, leaving an annular ledge 112 on which this outlet end member 80 rests. When the discharge head 14 is removed, the outlet end member 80 need be withdrawn rightward for a distance only equivalent to the length of this ledge 112 before coming adjacent the relieved portion indicated by the numeral 111, thereby making further rightward movement of the member 80 quite free from restraint. To complete the disassembly of the insert structure, the pump element 79 is next moved to a position beyond the ledge 112. Thereafter, the rod 107 can be withdrawn and the remaining pump elements are then easily removed.

Disposed at the left of the insert structure 75 is an inlet end member 115. To conserve space and increase the number of stages of the pump, we have shown this inlet end member as including an inward-extending wall 116 cooperating with the inward-extending wall 83 of the adjacent pump element 16 in defining an impeller chamber 117 in which one of the impellers

93 is positioned. This expedient can be dispensed with, if desired, permitting the incoming fluid to be delivered to the impeller 93 of the chamber 91 formed by the pump elements 76 and 77.

5 In addition, the inlet end member 115 provides another inward-extending wall 119 adjacent but spaced generally from the inlet head 13. This inward-extending wall 119 provides an opening of a size only slightly larger than the inner periphery of the sealing member 31 so as to receive this member, the joint at this point being insufficiently tight to prevent transfer of the inlet pressure of the pump to the space between this wall and the head 13. We prefer to form the inner surface 120 of the sealing member 31 so as to be a continuation of the inner surface of the inward-extending wall 119 so that these elements cooperate in guiding the incoming fluid to the first impeller.

20 In the embodiment shown in Figure 1, the inlet end member 115 is positioned in a cylindrical space 122 of the shell 11 which terminates at a radial shoulder 123 (best shown in Figures 1 and 3) and similar in function to the shoulder 70. 25 Abutting against the radial shoulder 123 is an annular portion 124 of the inlet end member 115. This inlet end member 115 also provides a centralizing ledge 125 fitting in the corresponding recess of the pump element 76. It is quite important, however, that this centralizing ledge should terminate short of the main portion of the pump element 76 to leave a small space 121. By this expedient, the shoulder 70 can remain the sole means taking leftward expansive thrust 30 from the insert structure 15 without transferring this thrust to the head 13.

The extreme left end of the inlet end member 115 provides an annular projection 128 which centralizes the member 115 by extending into a corresponding recess formed in the head 13. An 40 expansion-permitting means 129 is positioned in this recess to be clamped between the inlet end member 115 and the head 13, thereby permitting expansion of this member 115 in a manner similar to that previously described with reference 45 to the insert structure 15.

Another important feature of the invention resides in the design of the inlet and outlet end members 115 and 80 whereby they provide substantially circular chambers through which a hot 50 fluid flows, these chambers being of substantially constant radial dimension around the periphery of the shaft so that the massive cylindrical shell 11 will be uniformly heated at all peripheral portions opposite these members. The inlet end member 115 provides such a chamber, indicated by the numeral 130, bounded by the inward-extending walls 116 and 119 and by a cylindrical wall 131 which is desirably of substantially uniform thickness at all peripheral portions. The 55 upper end of this cylindrical wall 131 provides an opening 132 communicating openly with the inlet port 17, and it is desirable, in facilitating removal of the inlet end member 115, to make the outer periphery thereof slightly smaller in diameter than the cylindrical space 122 of the shell 11.

Likewise, the outlet end member 80 is preferably formed with its cylindrical wall 101 of substantially uniform thickness at all peripheral portions. This cylindrical wall 101 cooperates 70 with the annular wall 110 of the outlet end member 80 and with an end wall 133 adjacent the ring 100 in defining an outlet chamber 134 which communicates with the discharge of the last impeller and provides an opening 135 adjacent the

outlet port 21. The inner portion of the discharge chamber 134 is bounded by a cylindrical surface formed by the wall 27' of the head 14.

It is desirable to maintain the pressure in the chamber 43 of the head 14 at a pressure substantially equal to the inlet pressure of the pump. For this purpose, pipe means 136 is provided which communicates at one end with this chamber 43 and at the other end with the inlet circular chamber 130 through port means 137 10 formed in the cylindrical wall 131 and the adjacent portion of the cylindrical shell 11, as best shown in Figure 7. The chamber 43 communicates with the pipe means 136 through an opening 138 of the head 14, this opening threadedly receiving an outward-extending portion of the pipe means 136. It is a feature of the invention to provide a notch 139 for this outward-extending portion, this notch being cut into the rightward end of the cylindrical shell 11. By making the pipe 20 means in units which can be readily disconnected, for example, by use of flange means 139', it becomes possible to disconnect the pipe means adjacent one of these flange means so that the outward-extending portion thereof can be removed with the head 14.

In order that the expansion of the shell 11 shall be equalized at all peripheral sections to insure mating engagement between the insert structure 15 and the shoulder 70, it is likewise important 30 to use a supporting means for the enclosing structure of the pump which will insure this result. In addition, the supporting means to be described serves to prevent disalignment of the shell 11 with respect to the elements therein and 35 serves to maintain the alignment between the shaft 30 and the prime mover which, of course, is not subjected to the same high temperatures as is the pump.

This supporting means is best shown in Figures 40 1 and 2 and includes a hollow base member 140 resting upon a suitable foundation and traversing the entire space beneath the cylindrical shell 11. Extending upward from this base member 140 at opposite ends of the enclosing structure, and 45 preferably at opposite ends of the massive cylindrical shell 11, are two sets of pedestals, each set including two pedestals 141 extending upward on opposite sides of the enclosing structure. Suitably secured, as by welding, to opposite sides of the enclosing structure to rest upon the pedestals 141 are supporting means shown as comprising sets of arm members, each set including two arm members 145, as best shown in Figure 2. It is 50 desirable that these arm members 145 should extend outward from the shell at a position near the horizontal axis thereof so that transverse expansion of the enclosing structure can take place substantially equally above and below the horizontal plane of these arms. We prefer to weld the 55 arms 145 to the periphery of the massive forge cylindrical shell 11, and it is a very desirable feature of the invention that these arms should extend outward on opposite sides of the shell in substantially lateral alignment with the inlet and 60 outlet ports 17 and 21, respectively, so that any forces due to expansion of the pipes normally connected with the inlet and outlet fittings 16 and 20 will be delivered in a plane substantially common to that occupied by the pedestals. External 65 forces thus applied through the piping connected to the pump are thus prevented from disaligning the shell 11 longitudinally, or placing an unequal bending stress on this shell or the entire enclosing structure.

It is likewise desirable to use a supporting means for the pump which will compensate for longitudinal expansion of the enclosing structure. To this end, the pedestals are disposed between the members 140 and 145 and provision is made for expansion between these pedestals and the members 140 or 145. In the embodiment shown the pedestals are fixed to the base member 148 and provide upper surfaces 148 upon which the arm members 145 slidably rest. The arm members 145 are held down against the pedestals 141 by bolts 149.

The expansive forces to be compensated for are both lateral and longitudinal. Expansion laterally with respect to the shaft is not severe at either end of the pump but is compensated for by permitting the arm members 145 to slide on the upper surfaces 148. Such movement is made possible by making the bolt-receiving openings 150 slightly enlarged with respect to the bolts 149.

In order to maintain the axis of the shaft and of the shell 11 in a fixed vertical plane, and in order to equalize lateral expansion on opposite sides thereof, we provide each set of pedestals 141 with a longitudinal channel 152 slidably receiving a rib 153 on the adjacent portion of the enclosing structure. For example, this rib 153 may be welded to the lower portion of the massive cylindrical shell 11.

To compensate for longitudinal expansion of the enclosing structure, the arm members 145 at one end may be made to slide longitudinally on the corresponding pedestal by proper elongation of the openings 150. It is preferred to permit this longitudinal expansion to take place at the outlet end while precluding the same degree of longitudinal expansion at the inlet end. The enclosing structure is guided in this longitudinal expansion by the interengagement between the rib 153 and the longitudinal channel 152. This type of supporting means for the enclosing structure maintains the temperature of the massive cylindrical shell substantially uniform at all peripheral portions and permits longitudinal expansion without deformation of the base member 140, which is preferably hollow so that a cooling fluid can be circulated therethrough to maintain the entire base structure substantially cool at all times.

Referring particularly to Figure 8, the alternative construction shown therein is generally similar to that shown in Figure 1, with certain exceptions, some of which will be specifically noted. For example, the inlet end member of the modified construction is formed integrally with the first pump element adjacent the shoulder so that the inlet end member is a part of the insert structure. The entire internal structure can thus be withdrawn by removing only one of the two heads. As mentioned above, it is still desirable to maintain unrestrained from leftward or inward movement that portion of the insert structure extending to the left of the shoulder 70. For that purpose, the inlet end member is spaced from the inlet head 13 but provides the same general configuration except that it is centralized with respect to the opening 71 of the shoulder 70 by being made of a size to fit this opening. In addition, the cylindrical space 122 is smaller in the form shown in Figure 8, being of a diameter equal to that of the opening 71 of the shoulder 70.

So, also, the upper two-thirds or thereabouts of this first pump element in the modified form is relieved from contact with the shell for the complete length of this pump element to facili-

tate withdrawal, and any centralizing function of the unrelieved portion thereof shown in Figure 1 is made unnecessary in the embodiment of Figure 8 by the centralizing action of the opening 71 of the shoulder 70, in which opening a portion 5 of this pump element fits.

Another modification in the embodiment shown in Figure 8 is that the massive cylindrical shell is not relieved at 111 so that substantially cylindrical contact for the entire length of the outlet end member 80 is provided.

Another variation in the embodiment shown in Figure 8 is that the pin-receiving groove 108 extends completely through the last pump element toward the outlet end so that the rod 107 is withdrawable as soon as the outlet end member 80 is withdrawn. However, this outlet end member still provides the annular wall 110 for closing the small space 106 against free circulation of the hot fluid therethrough.

Also, the form shown in Figure 8 includes sealing members 200 and 200' corresponding, in general, to the sealing members 31 and 31' except that they provide passages for a cooling fluid which functions not only to maintain the sealing structure cool but also to cool the small throttled flow into the chamber 43, thereby preventing any possibility of flashing under adverse operating conditions. It will be noted that this chamber 43 is somewhat larger in the form of Figure 8 than in Figure 1, but the same general pipe means is provided for bypassing this chamber to the inlet pressure of the pump. While the construction of the throttle or balancing means 45 is approximately the same, the embodiment in Figure 8 eliminates the rotating vanes 62 and substitutes for the tapered portion 54 of the shaft 30 a cylindrical portion ending in the shoulder member or collar 56.

Various changes and modifications can be made without departing from the spirit of the invention as defined in the appended claims.

This application is a continuation-in-part of our application Serial No. 710,838, filed February 12, 1934.

We claim as our invention:

1. A pump of the character described, including: a cylindrical shell having an axial opening therethrough and inlet and outlet means near the ends thereof, there being a notch in the rearward end of said shell; an insert structure within said shell and including an inlet member at the forward end thereof communicating with said inlet means of said shell and an outlet member at the rearward end thereof communicating with said outlet means of said shell there being a passageway in the insert structure between said inlet and outlet members; head means for the front end of said shell; head means detachably secured to the rear end of said shell and providing a chamber therein; a shaft extending through said chamber to said insert structure; sealing pump elements in said passageway operatively connected to said shaft; means around said shaft at the outer end of said chamber; throttle means around said shaft between said chamber and said outlet member; and piping extending along the exterior of said shell, said piping having its forward end connecting through said shell with the interior of said inlet member and having the rearward end thereof connected to said chamber, said piping passing through said notch in the rearward end of said shell.

2. In a high-pressure hot-fluid rotary pump of the character described, the combination of: a

massive cylindrical shell providing inlet and outlet ports through the wall thereof near the respective inlet and outlet ends thereof, said shell providing an inward-extending ring in a plane perpendicular to the axis of said shell and lying between said ports and near said inlet port, said shell having forward and rearward supporting means, said forward supporting means being disposed on opposite sides of said shell and being substantially laterally aligned with said inlet port, and said rearward supporting means being disposed on opposite sides of said shell and being substantially laterally aligned with said outlet port whereby forces applied to said shell through the connection of inlet and outlet pipes to said ports will be transmitted directly through the wall of said shell in lateral direction to said supporting means; an insert structure in said cylindrical shell and including an inlet and an outlet section positioned on opposite sides of said ring, said insert structure providing an inlet communicating with said inlet port of said shell and providing an outlet communicating with said outlet port of said shell and a passageway between said inlet and outlet; pump elements in said passageway of said insert structure; a head closing the inlet end of said shell and forcing said inlet section into sealing engagement with said ring; and a head secured to the outlet end of said shell, said last-named head engaging said outlet section of the insert structure and forcing the same against said ring.

3. In a high-pressure hot-fluid rotary pump of the character described, the combination of: a cylindrical shell providing inlet and outlet ports through the walls thereof near the respective inlet and outlet ends thereof, said shell having forward and rearward supporting means, said forward supporting means being disposed on opposite sides of said shell and being substantially laterally aligned with said inlet port, and said rearward supporting means being disposed on opposite sides of said shell and being substantially laterally aligned with said outlet port whereby forces applied to said shell through the connection of inlet and outlet pipes to said ports will be transmitted directly through the wall of said shell in lateral direction to said supporting means; an insert structure in said shell and including an inlet section and an outlet section, said insert structure having an inlet communicating with said inlet port of said shell and an outlet communicating with said outlet port of said shell and a passageway connecting said inlet and outlet, there being sealing means between said insert structure and said shell in a position between said inlet port and said outlet port; pump elements in said passageway of said insert structure; and head means closing the ends of said shell and holding said inlet and outlet sections in sealing engagement with said sealing means.

4. In a high-pressure hot-fluid rotary pump of the character described, the combination of: a massive cylindrical shell providing substantially vertical radial inlet and outlet ports therethrough near the respective inlet and outlet ends thereof at the upper side of the cylindrical shell; two sets of supporting means, each set including supporting means disposed on opposite sides of said shell, one set of supporting means being substantially laterally aligned with said inlet port and the other set of supporting means being substantially laterally aligned with said outlet port whereby forces applied to said shell

through the connection of piping to said ports will be transmitted laterally through the wall of said shell to said supporting means without producing substantial forces tending to bend said shell between said sets of supporting means; head means closing the opposite ends of said shell; and a pump structure within said shell for pumping a hot fluid therethrough.

5. In combination in a hot-fluid rotary pump adapted to pump fluids at high temperatures: a massive cylindrical shell providing a port extending therethrough to communicate with a cylindrical zone defined by said shell; head means closing the ends of said massive cylindrical shell; an end member within said cylindrical zone and providing a cylindrical wall of substantially constant thickness at all peripheral portions, the outer portion of said cylindrical wall being only slightly smaller than said cylindrical zone, said cylindrical wall providing an opening adjacent said port but otherwise extending completely around the inner periphery of said shell in close proximity thereto and to said head means to define a circular chamber whereby a hot fluid entering said circular chamber will equally heat all portions of said cylindrical wall and the adjacent portions of said cylindrical shell; and rotary pump means for moving a hot fluid through said port and through said circular chamber.

6. In combination in a hot-fluid rotary pump adapted to pump fluids at high temperatures: a massive cylindrical shell providing an inlet port extending therethrough near the inlet end of said shell to communicate with a cylindrical space defined by said shell; head means closing said inlet end of said shell; an inlet end member within said cylindrical space and providing a cylindrical wall of substantially constant thickness and which is only slightly smaller in outer diameter than said cylindrical space, said cylindrical wall providing an opening adjacent said inlet port but otherwise extending completely around the inner periphery of said cylindrical space, said inlet member providing an inward-extending wall adjacent said head means at a position adjacent one side of said inlet port and another inward-extending wall providing an opening and positioned adjacent the other side of said inlet port, said inward-extending walls and said cylindrical wall forming a circular chamber coaxial with the axis of said shell whereby a hot fluid entering through said inlet port will equally heat all portions of said cylindrical wall and the adjacent portions of said cylindrical shell; rotary means communicating with said opening of said inward-extending wall for moving a hot fluid through said inlet port and said circular chamber; and means for discharging said hot fluid from said cylindrical shell.

7. In combination in a hot-fluid rotary pump adapted to pump fluids at high temperatures: a massive cylindrical shell providing inlet and outlet ports extending therethrough to communicate respectively with a cylindrical space and a cylindrical cavity formed by said shell, said shell providing an inward-extending annular shoulder at the junction of said cylindrical space and said cylindrical cavity, said annular shoulder being disposed between said inlet and outlet ports; a pump element in said cylindrical cavity and providing an annular surface mating with said annular shoulder; an inlet end member opposite said inlet port and providing a cylindrical wall of substantially uniform thickness at all

peripheral portions thereof and defining a circular chamber positioned on the inlet side of said annular shoulder and communicating with said pump element whereby a hot fluid entering said 5 circular chamber will equally heat all peripheral portions of said cylindrical wall and all adjacent peripheral portions of said cylindrical shell, said cylindrical wall providing an opening through which said inlet port communicates with 10 said circular chamber; an outlet end member disposed adjacent said outlet port and providing an outer cylindrical wall of substantially uniform thickness at all peripheral portions, said cylindrical wall providing an opening communicating between said outlet port and a circular chamber bounded by said cylindrical wall whereby the hot fluid moving through this circular chamber will equally heat all peripheral portions of said cylindrical wall and all adjacent peripheral 15 portions of said cylindrical shell, this circular chamber being on the same side of said annular shoulder as said pump element; means for retaining said annular surface of said pump element in pressural mating contact with said 20 annular shoulder; and means for moving a hot fluid through said inlet port, the adjacent circular chamber, said pump element, and through the other circular chamber and said outlet port.

8. In combination in a hot-fluid rotary pump 30 adapted to pump fluids at high temperatures: a massive cylindrical shell providing a cylindrical space and a port extending outward through said shell to communicate therewith; head means for closing the adjacent end of said cylindrical shell 35 and providing an opening coaxial with the axis of said shell; a shaft of considerably smaller diameter than said opening and extending therethrough to define an annular space; an annular member detachably connected to said head means 40 and extending through said annular space and providing an end surface disposed in said cylindrical space; an end member disposed in said cylindrical space and providing an inward-extending wall with an opening therein of sufficient diameter to receive the end of said annular member, said inward-extending wall providing a surface terminating at said opening thereof in a zone immediately adjacent said end surface of said annular member to cooperate therewith in 45 defining a fluid-guiding wall means bounding an internal passage, said passage communicating with said port; and means for moving a hot fluid through said internal passage along said fluid-guiding wall means.

55 9. In combination in a hot-fluid rotary pump adapted to pump fluids at high temperatures: an enclosing structure including a massive one-piece cylindrical shell and head means detachably connected to opposite ends thereof, said massive cylindrical shell including inlet and outlet ports 60 communicating with the interior of said shell, the interior of this shell providing a cavity closed at its outer end by one of said head means and terminating at its inner end at a shoulder extending inward from said shell adjacent said inlet port on the side thereof toward the outlet port and extending completely around the inner periphery of said shell, said shoulder providing an opening of smaller diameter than said cavity; a 65 inlet end member disposed within said shell adjacent said inlet port and including a cylindrical wall of substantially uniform thickness at all peripheral portions thereof, the outer surface of said cylindrical wall being substantially equally spaced from said cylindrical shell whereby a

hot fluid entering said inlet end member will equally heat the adjacent peripheral portions of said shell, said cylindrical wall providing an opening therein communicating between said inlet port and the interior of said inlet end member; an outlet end member adjacent said outlet port and providing a cylindrical wall of substantially uniform thickness at all peripheral portions, the outer portion of said cylindrical wall being substantially equally spaced from said cylindrical shell whereby a hot fluid flowing through said outlet end member will equally heat the adjacent peripheral portions of said shell, this cylindrical wall providing an opening therein communicating between said outlet port and the interior of said outlet end member; a plurality of abutting pump elements disposed in said cylindrical shell between said shoulder and said outlet end member, that pump element of said plurality of pump elements which is adjacent 10 said annular shoulder providing an annular surface mating with said shoulder; a shaft extending through said heads; impeller means secured to said shaft for moving a hot fluid from said inlet port through said inlet end member, 15 through said pump elements, through said outlet end member, and through said outlet port; outboard bearings secured to said removable heads and positioned therebeyond for journaling said shaft; supporting means extending outward from said cylindrical shell on opposite sides thereof near the horizontal axis of said shell; and pedestal means for supporting said cylindrical shell through said supporting means.

10. In combination, in a hot fluid rotary pump 30 adapted to pump fluids at high temperatures: an enclosing structure including a massive one-piece cylindrical shell and head means at opposite ends thereof and detachably connected to at least one of said ends, said massive cylindrical 35 shell including inlet and outlet ports communicating with the interior of said shell, the interior of said shell providing a cavity closed at its outer end by one of said head means and terminating at its inner end at a shoulder extending inward from said shell adjacent said inlet port on the side thereof toward the outlet port and extending completely around the inner periphery of said shell, said shoulder providing an opening of smaller diameter than said cavity; a 40 plurality of abutting stationary pump elements disposed in said cavity between said inlet and outlet ports and including a fluid passage communicating with said ports, one of said stationary pump elements providing an annular surface 45 mating with said shoulder, said massive cylindrical shell being of substantially uniform thickness between said ports, and said pump elements being so formed that all peripheral portions thereof in any plane perpendicular to the axis 50 of said shell are of substantially uniform thickness whereby to equalize heat and expansion at all peripheral portions of said shell and said pump elements and thereby prevent warping of said shoulder to maintain said annular surface 55 in mating relationship with said shoulder; an outlet end member providing a passage communicating between the outlet port and one of said pump elements; a ring of gasket character disposed near the outer periphery of said outlet end 60 member between said member and the head means at the outlet end of said shell to compensate for excess expansion of said insert structure and maintain said annular surface in mating relationship with said shoulder; and means inside said 65 70 75

insert structure for forcing hot fluid through said fluid passage.

11. In combination, in a hot fluid rotary pump adapted to pump fluids at high temperatures: an enclosing structure including a massive cylindrical shell and head means closing the ends of said shell, the interior of said shell providing a cylindrical cavity; a plurality of pump elements providing lower annular portions of substantially the same radius as the radius of said cylindrical cavity and resting on the lower portion of said cylindrical shell, the upper portion of each pump element being formed on a somewhat smaller radius to provide a relieved portion extending more than half way around the upper portion of each pump element to define a small space between the upper portion of each pump element and said cylindrical shell, each pump element providing a groove at the upper end thereof; a removable rod extending through the grooves of said pump elements and being of such size as to engage the upper portion of said cylindrical cavity to lock the pump elements in position; means at the outlet end of said pump elements providing an annular wall of a diameter substantially equal to that of said cylindrical cavity to restrict entrance of hot fluid into the space between the upper portions of said pump elements and said shell and thereby prevent free circulation of hot fluid through this space; means for axially compressing the pump elements; and means for moving a hot fluid through said pump elements.

12. In combination, in a hot-fluid rotary pump: a cylindrical shell defining a cylindrical cavity and providing inlet and outlet ports, said shell further providing an inwardly projecting annular shoulder in said cylindrical cavity between said inlet and outlet ports; head means closing the ends of said cylindrical shell; an insert structure in said cylindrical cavity and including an end member on the inlet-port-side of said shoulder positioned in alignment with said inlet port, said end member providing a cylindrical wall of substantially constant thickness at all peripheral portions, the outer portion of said cylindrical wall being only slightly smaller than said cylindrical cavity, said cylindrical wall having an opening adjacent said inlet port but otherwise extending completely around the inner periphery of said cylindrical shell in close proximity thereto and to said head means to define a circular chamber whereby a hot fluid entering said circular chamber will equally heat all portions of said cylindrical wall and the adjacent portions of said cylindrical shell, said insert structure also including a portion extending from said outlet port to the outlet-port-side of said shoulder and mating with said shoulder and resting upon the lower inner portion of said cylindrical shell with a small space between its upper peripheral portion and the upper inner portion of said shell, that portion of said insert structure which is proximate to said outlet port being in communication with said outlet port and providing an annular wall of a diameter substantially equal to that of said cylindrical cavity to restrict entrance of hot fluid into the aforesaid small space and thereby prevent free circulation therethrough; means permitting longitudinal expansion of said insert structure on the outlet-port-side of said shoulder relative to said cylindrical shell to compensate for ex-

cess expansion of said insert structure and to maintain pressural contact of said mating surface of said insert structure with said shoulder; and means for moving hot fluid from said inlet port through said insert structure and thence through said outlet port. 5

13. In a high-pressure hot-fluid rotary pump of the character described, the combination of: a massive cylindrical shell providing inlet and outlet ports through the wall thereof near the respective inlet and outlet ends thereof, said shell providing an inward-extending ring in a plane perpendicular to the axis of said shell and lying between said ports and near said inlet port, said shell having supporting means disposed on opposite sides thereof and substantially laterally aligned with said inlet and outlet ports, whereby forces applied to said shell through the connection of inlet and outlet pipes to said ports will be transmitted directly through the wall of said shell in lateral direction to said supporting means; an insert structure in said cylindrical shell and including an inlet and an outlet section positioned on opposite sides of said ring, said insert structure providing an inlet communicating with said inlet port of said shell and providing an outlet communicating with said outlet port of said shell and a passageway between said inlet and outlet; pump elements in said passageway of said insert structure; a head closing the inlet end of said shell and forcing said inlet section into sealing engagement with said ring; and a head secured to the outlet end of said shell, said last-named head engaging said outlet section of the insert structure and forcing the same against said ring. 25

14. In a high pressure hot fluid rotary pump of the character described, the combination of: a massive cylindrical shell having substantially vertical radial inlet and outlet ports extending through the wall thereof between its ends; head means closing the opposite ends of said shell, at least one of said head means being detachable; supporting means extending from said shell on opposite sides in substantially lateral alignment 40 with said inlet and outlet ports, whereby forces or loads applied to said shell through the connection of piping to said ports will be transmitted laterally through the wall of said shell to said supporting means without producing substantial forces or loads tending to distort said shell; and a pump structure within said shell for pumping a hot fluid therethrough. 50

15. A combination as defined in claim 11 in which the cylindrical shell has an outlet port and 55 in which said rotary pump means includes an insert structure providing a plurality of pump elements and a second end member, said second end member being within said cylindrical zone in communication with said outlet port, said pump 60 elements resting upon said cylindrical shell with a small space between their upper peripheral portions and said cylindrical shell, that portion of said insert structure which is proximate to said outlet port providing an annular wall of a diameter substantially equal to that of said cylindrical zone to restrict entrance of hot fluid into the aforesaid small space and thereby prevent free circulation therethrough. 65

CERTIFICATE OF CORRECTION.

Patent No. 2,161,695.

June 6, 1939.

GEORGE E. BIGELOW, ET AL.

It is hereby certified that error appears in the printed specification of the above numbered patent requiring correction as follows: Page 2, second column, line 3, for the word "screws" read screw; page 4, first column, line 71, for "lace" read place; page 6, first column, line 8, for "member 148" read member 140; and second column, line 62, claim 1, strike out the word " sealing" and insert the same after the semicolon and before "means" in line 64, same claim; and that the said Letters Patent should be read with this correction therein that the same may conform to the record of the case in the Patent Office.

Signed and sealed this 11th day of July, A. D. 1939.
